UNITED STATES PATENT OFFICE

RICHARD J. BRITTAINE, JR., OF BLOOMFIELD, AND OTTO W. YOUNG, OF EAST ORANGE, NEW JERSEY, ASSIGNEES TO GENERAL MOTORS CORPORATION, OF DETROIT, MICHIGAN, A CORPORATION OF DELAWARE

JOURNAL BOX

Application filed November 5, 1930. Serial No. 493,488.

This invention relates to journal boxes and comprises all the features of novelty herein disclosed. An object of the invention is to provide a journal box having improved means of retaining the bearing and simplifying manufacture. Another object is to provide a journal box having improved means of distributing and retaining lubricant and having a structure permitting easy assembly and inspection.

To these ends and to improve generally and in detail upon devices of this character, the invention also consists in the various matters hereinafter disclosed and claimed. In its broader aspects the invention is not necessarily limited to the specific construction selected for illustrative purposes in the accompanying drawings in which

Fig. 1 is a central vertical section of a journal box.

Fig. 2 is one-half end view and one-half central cross section to a smaller scale than Fig. 1.

Fig. 3 is a vertical sectional view of a sealing plate or ring.

Fig. 4 is an interior side view of the sealing plate.

Fig. 5 is an enlarged sectional view on line 5-5 of Fig. 4.

Fig. 6 is an enlarged fragmentary section on line 6-6 of Fig. 4.

Fig. 7 is an end view of the open end of the box.

Fig. 8 is a fragmentary vertical section at the outer end of the box.

Fig. 9 is a rear view of the thrust block, enlarged.

Fig. 10 is a vertical sectional view of the retaining ring and

Fig. 11 is a rear view of the retaining ring.

The numeral 10 indicates a shaft or axle carrying a sleeve 12 for roller bearings 14 having cage rings 16. The rollers run in an outer sleeve 18 in the bore of an axle box 20.

The top of the box has a cross recess receiving a lower seat plate 22 having holding lugs 24 entering cavities in the box, the seat plate also having upwardly extending lugs 26 which enter slots at the ends of an upper seat

plate 28 carrying the load. The box has

pedestal flanges 30 covered by wear plates 32 and the sides of the box are protected by wear plates 34.

The inner end of the box is closed by a sealing plate 36 having a flange 38 bolted to the box with a gasket interposed. On the outside, the sealing plate has an extension flange 40 bounding a peripheral drain groove 42 which is surrounded by a slinger 44 in the form of an angled ring attached by screws 60 to a wheel hub. Thus, water is effectively drained away from the box. On the inside of the box, the sealing plate has an arcuate extension 46 abutting against and locating one end of the bearing sleeve 18. The plate 65 also has a relief groove 48 which extends around the upper half and terminates at vertical, flat extension walls 50. The groove receives surplus lubricant expelled axially from the rollers and drains it back into the 70 bottom of the box. A hardened face 52 on the plate serves as a guide for the adjacent bearing race ring 16 and limits endwise movement of the rollers.

The sealing plate further has an arcuate 75 internal groove 54 merging at one side with an outwardly facing trap groove 56. A portion of the width of the groove 54 is provided with straight walls 58 extending downwardly from axle level to terminate at the upper 80 edges of openings 60 extending through the sealing plate, the lower walls of the openings being formed by oppositely inclined surfaces 62 on a partition plate 64. The groove 54 is arranged directly outside of a lubricant collecting and slinging rib 66 on the axle and lubricant, thrown off from the upper half of the axle, is trapped by the groove 56 and drained to the inclined surfaces 62. The inner end of the sleeve projects within the sealing plate to a point opposite to the groove 54 and forms an additional lubricant collecting and slinging rib. Such lubricant and lubricant thrown from the low point of the axle is drained down the inclines, through 85 the openings 60, and into the space 68 at the bottom of the box below the sleeve 18. The partition 64 prevents oil surging about in the box from splashing up to the axle.

The outer end of the box has an integral 100

end wall 70 and an enlargement 71 forming a portion of a lubricant reservoir having a filling opening 72. The outer end of the box has at the top an inclined opening 74 closed by a detachable lid 76 of generally rectangular outline. A thrust block 78 opposes the end of the axle and is provided with a slot 79 for a wick 80 which elevates lubricant from the reservoir to the axle. The thrust block is 10 preferably made of bronze cast around a flanged nut 82 which is externally square and internally threaded to receive a clamping screw bolt 84. The thrust block has a handle 86 by which it can be lifted out of the box 15 through the opening 74 when the lid 76 and the bolt 84 are removed. Likewise removable through the lid opening are spacing plates 88 having hand holes 90. The clamping bolt 84 holds the thrust block and spacing plates 20 rigidly against a finished face on the box end wall 70. A portion of the thrust block is externally square or provided with interrupted flat edges 91 which fit in a box recess formed by pairs of spaced lugs 92 and a bottom shelf 94, all cast on the inner side of the 25 end wall 70. The lugs 92 hold the thrust block from rotating and the shelf 94 prevents the thrust block and spacing plates from dropping out of reach when the screw 30 bolt 84 is removed.

An important feature of the invention resides in a retaining ring which is located near the outer end of the box in a position to co-operate with the bearings and the wick. Beyond the bored out portion of the box are 35 two arcuate abutment faces 96 which extend from the sides of the lid opening 74 to the lubricant reservoir. They abut against a pair of co-extensive arcuate ribs 98 on a ring 100 which fits in the bore of the box. One side 40 of the ring has a portion abutting against and retaining the bearing sleeve 18 and another portion which is hardened to guide the adjacent cage ring 16 of the bearings. At 45 their lower ends, the arcuate ribs 98 have a pair of upwardly extending lugs 102 and a pair of downwardly extending lugs 104 whose side walls are spaced apart to form a slot 106 embracing and supporting the wick 50 80. The retaining ring is cut away at the bottom as at 108 to form a notch affording direct communication between the lubricant reservoir and the bearings. At the top, there is an opening 110 for surplus lubricant to 55 escape from the bearings, this opening also serving as an inspection opening when the lid is removed. The ribs 98 are spaced apart at the top a distance approximately equal to the width of the opening 74 of the box so that 60 they offer no obstruction to the withdrawal of the thrust block. The ring is held from rotation by its lugs 104 which project downwardly and fit in a slot formed by the vertical side walls of the enlargement 71. The 65 interior of the box and its manufacture are

simplified by utilizing a retaining ring having an abutment against faces which are spaced from the end of the bore, thus leaving a clearance for the wheel when grinding the bore.

We claim:

1. In a device of the character described, a journal box, a shaft extending into the box, a bearing between the shaft and the box, a ring fitting in the bore of the box and having a guide face on one side for the bearing, the other side of the ring having arcuate ribs engaging abutment faces on the box, the ribs being spaced apart at the bottom to form a slot for a wick, and a shaft-engaging wick 80 in the slot; substantially as described. 70

2. In a device of the character described, a journal box, a shaft extending into the box, a bearing between the shaft and the box, a ring fitting in the bore of the box and having a guide face on one side for the bearing, the other side of the ring having arcuate ribs engaging abutment faces on the box, the ribs being spaced apart at the bottom to form a slot for a wick, a wick in the slot, a thrust 85 block carried by the end wall of the box, the end of the box having an opening, and the ribs being spaced apart at the top for removal of the thrust block through the opening; substantially as described. 90

3. In a device of the character described, a journal box, a shaft extending into the box, a bearing between the shaft and the box, a ring fitting in the bore of the box and having a guide face on one side for the bearing, the other side of the ring having a projecting rib engaging an abutment face on the box, and the ring having an opening near the top and an opening at the bottom affording 100 communication between the bearing and the end of the box; substantially as described. 105

4. In a device of the character described, a journal box, a shaft extending into the box, a bearing between the shaft and the box, a 110 ring fitting in the bore of the box and having a guide face on one side for the bearing, the other side of the ring having a projecting rib engaging an abutment face on the box, the ring having an inspection opening near the top, and the box having a lid covering an opening opposite to the ring opening; substantially as described. 115

5. In a device of the character described, a journal box, a shaft extending into the box, a bearing between the shaft and the box, a ring fitting in the bore of the box and having a guide face on one side for the bearing, the other side of the ring having arcuate ribs, the ribs being spaced apart at the bottom to leave a slot and having upwardly and downwardly extending lugs at the sides of the slot; substantially as described. 120

6. In a device of the character described, a journal box, a shaft extending into the box, 130

- a bearing between the shaft and the box, a ring fitting in the bore of the box and having a guide face on one side for the bearing, the other side of the ring having arcuate 5 ribs, the ribs being spaced apart to form a slot, and the ring having a notch opposite to said slot; substantially as described.
7. In a device of the character described, a journal box, a shaft extending into the box, a bearing between the shaft and the box, a ring fitting in the bore of the box and having a guide face on one side for the bearing, the other side of the ring having arcuate ribs 10 engaging abutment faces on the box, the end of the box having an opening, a thrust block carried by the end wall of the box, and the ribs being spaced apart opposite to said opening for removal of the thrust block; substantially as described.
- 15 8. In a device of the character described, a journal box, a shaft extending into the box, a bearing between the shaft and the box, the end wall of the box having internally projecting lugs forming an upwardly open 20 recess, a thrust block in said recess, the box having an opening above said recess for removal of the thrust block therefrom, and a bearing guide ring fitting in the bore of the box between the bearing and the adjacent edge of 25 the opening; substantially as described.
9. In a device of the character described, a journal box, a shaft extending into the box, a bearing between the shaft and the box, a thrust block detachably secured to the end 30 wall of the box, the box having an opening above said thrust block, and a bearing guide ring fitting in the bore of the box and spaced from the end wall; substantially as described.
- 35 10. In a device of the character described, a journal box, a shaft extending into the box, a bearing between the shaft and the box, the box having an integral end wall closing one 40 end and a cylindrical bore extending to the open end, a ring inserted in the bore of the box through the open end to guide the outer end of the bearing, means on the box between the outer end of the cylindrical bore and the end wall to engage and hold said ring spaced 45 from the end wall, and a thrust block carried in the box at the outer side of the ring; substantially as described.
- 50 11. In a device of the character described, a journal box, a shaft extending into the box, a bearing between the shaft and the box, a ring secured to the box and having an extension projecting into the box towards the bearing, said extension having a relief groove 55 adjacent to the outer periphery of the bearing, the ring having an internal collecting groove merging at the side with an outwardly facing trap groove and the ring having an extension outside the box and provided with an external drain groove; substantially as described.
- 60 12. In a device of the character described,
- a journal box, a shaft extending into the box, a bearing and a bearing sleeve between the shaft and the box, a ring secured to the box and having an extension projecting into the box to engage the bearing sleeve, a guide face 70 on the ring adjacent to the bearing, a relief groove between the guide face and the sleeve-engaging extension, a slinger on the shaft, and the ring having an internal collecting groove adjacent to the slinger; substantially as described.
- 75 13. In a device of the character described, a journal box, a shaft extending into the box, a bearing and a bearing sleeve between the shaft and the box, a ring secured to the box and having an extension projecting into the box to engage the bearing sleeve, a guide face 80 on the ring adjacent to the bearing, and a relief groove between the guide face and the sleeve-engaging extension; substantially as described.
- 85 14. In a device of the character described, a journal box, a shaft extending into the box, a bearing between the shaft and the box, a ring secured to the box and having an extension projecting into the box towards the bearing, said extension having a relief groove adjacent to the outer periphery of the bearing, the ring having an internal collecting groove, and the shaft carrying a bearing 90 sleeve projecting within the ring and terminating at a point opposite to the internal groove to form a slinger; substantially as described.
- 95 15. In a device of the character described, a journal box having an end wall and an opening, a shaft extending into the box, a bearing between the shaft and the box, the box having an abutment face spaced inwardly from the end wall, a ring fitting in the bore 100 of the box at the end of the bearing and having projections spaced apart at the box opening and engaging said abutment face, and a thrust block opposite to the end of the shaft and removable laterally through the box 105 opening and between the spaced projections at the outer side of the ring; substantially as described.
- 110 In testimony whereof we hereunto affix our signatures.
- 115 RICHARD J. BRITTAINE, JR.
OTTO W. YOUNG.
